UNITED STATES PATENT OFFICE.

WILLIAM H. THOMPSON, OF BECKLEY, WEST VIRGINIA.

CLOCK-PENDULUM.

SPECIFICATION forming part of Letters Patent No. 731,244, dated June 16, 1903.

Application filed July 15, 1902. Serial No. 115,630. (No model.)

To all whom it may concern:

Be it known that I, WILLIAM H. THOMPSON, a citizen of the United States, residing at Beckley, county of Raleigh, and State of West Virginia, have invented certain new and useful Improvements in Clock-Pendulums, of which the following is a specification.

This invention relates to clocks, and more especially to the pendulum; and the object thereof is to provide a more simple and perfect regulator and to do away with the incessant ticking due to the parts of the escapement mechanism coming in contact with each other, which is very annoying to some 15 people.

A further object is to provide a novel means of adjusting the pendulum without the necessity of stopping the clock.

The invention resides in the novel features, 20 combinations, and adaptations of the several parts, which will be more fully set forth in the specification and recited in the appended claims, reference being had to the drawings, in which—

25 Figure 1 is a vertical section of the clock, omitting part of the works for the sake of clearness and showing the pendulum attached; Fig. 2, a top plan view with pendulum omitted; Fig. 3, a detail of the bracket and bearings of the worm-screw; Fig. 4, a detail of the leading-bar and pendulum-bob, and Fig. 5 a perspective of the adjustment of the pendulum-cord.

To the back of the frame 1 is detachably 30 and adjustably secured a bracket 2, which is bent at right angles at 3 and extends inwardly toward the front of the clock, forming a bearing for an adjusting-piece 4, carrying the bearing-socket 5, in which the lower end 35 of the worm-screw 6 is journaled. Just above the right-angular bend 3 the bracket is provided with ears or lugs 7, having downwardly-inclined slots 8, which permit the adjustment of the bracket. The upper part 40 of the bracket is extended for a short distance above the framework and is then bent at right angles to form a support for the bearing 9, in which is journaled the upper end of the worm-screw 6. The worm-screw 6 has a 45 shoulder 10, which abuts against the bottom of the bearing 9 and prevents it from rising out of its lower bearing 5. Passing through

the bearing is an elongation of the worm-screw, and secured to the top thereof is a horizontal balance-bar 11, having at one end a 55 counterbalance-weight 12 and at the other end a ball-and-socket joint 13. In gear with the clock-train is a toothed wheel 23, which meshes with the worm-screw 6 and gives the several parts of the pendulum motion. 60

Located in the top of the clock-case in nearly vertical alinement with the worm-screw is a block 14, to which is attached a U-shaped bracket 15, bent downward at its forward end to form a bearing for one end of a 65 winding-drum 16. The other end of the drum is supported in a lug 17, which is rigidly secured to the bracket.

Attached at one end to the winding-drum is a silk cord 18, which passes up through an 70 aperture 19 in the bracket between the lug 17 and the downwardly-bent portion. From the aperture the cord passes over and down through the cut-out portion of the bracket, which forms the U shape spoken of previously. 75

Attached to the lower end of the cord 18 is the pendulum-bob 20, which has on its lower end the ball-and-socket joint 21. Connected to the ball-and-socket joint is a leading-bar 80 22, which assists the pendulum in its giratory or planetary movement.

In operation the clock must be perfectly level, so that the pendulum-bob 20 hangs in perfect vertical alinement with the worm-screw 6. When the clock is started, the horizontal balance-bar 11 travels in a rotary direction from right to left, as indicated by the arrow in Fig. 2, and carries with it or pulls the leading-bar 22 and the pendulum-bob 20 85 90 after it, as shown in dotted lines in Fig. 2. The bob is raised or lowered by means of the winding-drum, thus regulating the speed of the clock. Turning to the right shortens the cord and increases the speed, and of course 95 just the opposite will decrease the speed.

Having thus described my invention, what I claim as new, and desire to secure by Letters Patent, is—

1. In a clock, the combination with a worm-screw adapted to be driven by the clock-train, of a rotary balance-bar centrally secured to the end of the worm-screw and having a weight on one end, a freely-suspended pen-

dulum, and a leading-bar pivoted to the pen-
dulum and to the other end of the balance-
bar.

2. In a clock, the combination with a worm-
screw, means for supporting said worm-screw,
means for adjusting said worm-screw within
said supporting means, and means for ad-
justing said supporting means.

3. In a clock, the combination with a worm-
screw, means for rotating said worm-screw,
of a bracket for supporting said worm-screw,

ears on said bracket, slots in said ears where-
by said bracket is adjusted with relation to
said rotating means, and an adjusting-piece
on said bracket whereby the worm-screw is 15
adjusted.

In testimony whereof I hereunto affix my
signature in presence of two witnesses.

WILLIAM H. THOMPSON.
